UNITED STATES PATENT OFFICE.

WILLIAM F. CAPITAIN, OF CHICAGO, ILLINOIS.

DESIGN FOR A FONT OF PRINTING-TYPE.

SPECIFICATION forming part of Design No. 16,105, dated May 26, 1885.

Application filed February 19, 1885. Term of patent 3½ years.

To all whom it may concern:

Be it known that I, WILLIAM F. CAPITAIN, a citizen of the United States of America, residing at Chicago, in the county of Cook and State of Illinois, have invented and produced 5 a new and original Design for a Font of Printing-Type, of which the following is a specification, reference being had therein to the accompanying printed specimens.

10 My invention relates to a new design for a font of printing-type.

The letters and numerals are inclined backward at an angle of about twenty-five degrees, and are all formed of lines of equal and uniform thickness.

15 The corners of the capital letters B, C, D, G, J, O, P, Q, R, S, U, OE, and Co., and most of the lower-case letters, and most of the numerals, and the character \$, and the interrogation- 20 mark ? are formed by straight lines inclined at an angle of about forty-five degrees from the lines forming the other portions of these letters, numerals, and characters. The top of the letter A and the bottom of the letters V 25 and W are formed by horizontal lines having angular connections with the side lines of these letters. The middle lines of W cross each other, and their upper ends are connected by a horizontal line. In the word "AND" the 30 letter N is provided with upper and lower cer- 35 iph-lines extending the whole length of the word, and the front line of the letter extends to the upper ceriph, and the back line extends to the lower ceriph, and the letters A and D are formed between the cerips.

In the abbreviation "Co." the line forming the upper front portion of C extends downward across the upper line of o.

35 The tail of the small letter g, connecting with 40 a straight oblique line which crosses the lower left corner line of the letter, extends forward, close to and parallel with the bottom line and beyond the front of the body of the letter, and then by a very short downward curve is 45 returned backward, close to and parallel with its upper portion. From the upper right cor-

ner of this letter g a short straight line extends obliquely forward and upward.

The lower portion of the back line of the lower-case letter b, and the front lines of d and 50 U, and the upper portions of the back lines of m, n, p, and r, and the front line of q extend beyond the connections of these lines with the corner lines of these letters.

The tail of the lower-case letter y is formed 55 by the continuation of its front line, which is extended downward a short distance below its connection with the corner line, and then by a double angle is inclined and extended backward, under, close to, and parallel with the 60 bottom line of the body of the letter.

What I claim as new, and desire to secure by Letters Patent, is—

The design for a font of printing-type of broad backwardly-inclined letters, in which 65 the forward portions of B, D, P, and R, the lower portion of U, J, and the whole of CGO, Q, S, and the most of the lower-case letters and the numerals consist of straight obtuse-angled lines; the middle lines of W cross each other, 70 and their upper ends are connected by a horizontal line, the upper portion of the tail of g connects by an acute angle with a straight oblique line, and extends forward and backward parallel with the bottom of the body of the letter; 75 the lower portion of the back line of b, and the front lines of d and n, and the upper portions of the back lines of m, n, p, and r, and the front line of q extend beyond the connections of these lines with the corner lines of 80 these letters; the front line of y by a double angle is extended backward parallel with the bottom line of the letter, these and the other portions of the design being substantially as described and shown.

85 In testimony whereof I have affixed my signature in presence of two witnesses.

WILLIAM F. CAPITAIN.

Witnesses:

THOS. WILSON,
JAMES HAWKINS.
